UNITED STATES PATENT OFFICE

WILLIAM G. KEITH AND JOSEPH A. MANARIK, OF CHICAGO, ILLINOIS, ASSIGNEES TO
WELSBACH TRAFFIC SIGNAL COMPANY, OF PHILADELPHIA, PENNSYLVANIA, A
CORPORATION OF DELAWARE

DESIGN FOR A LOADING ZONE SIGNAL PLATFORM

Application filed February 19, 1932. Serial No. 42,942. Term of patent 14 years.

To all whom it may concern:

Be it known that we, WILLIAM G. KEITH and JOSEPH A. MANARIK, citizens of the United States, both residing at Chicago, in the county of Cook and State of Illinois, have invented a new, original, and ornamental Design for a Loading Zone Signal Platform, of which the following is a specification, reference being had to the accompanying drawing, forming a part thereof.

Figure 1 is a perspective view of a loading zone signal platform embodying our new design, comprising an elongated platform for use by passengers awaiting a public convey-

ance having an enlarged end portion with signal lights disposed thereon and having an upright supporting member extending from the platform for holding a reflecting member adjacent the upper end thereof.

Fig. 2 is a side elevational view taken from the side opposite to that of Figure 1.

We claim:

The ornamental design for a loading zone signal platform substantially as shown and described.

WILLIAM G. KEITH.
JOSEPH A. MANARIK.
